(57) **CLAIM**

The ornamental design for an aerial vehicle, as shown and described.

DESCRIPTION

This application incorporates by reference in its entirety each of the following U.S. Design patent application Ser. Nos., filed on the same day herewith:

29/654,662, titled "Battery"

29/654,663, titled "Camera"

29/654,665, titled "Camera With Gimbal"

FIG. 1 is a top rear perspective view of an aerial vehicle showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 6 Drawing Sheets
